[57] ABSTRACT

A replaceable tire tread belt has radially outer and inner peripheral surfaces and a pair of opposite side surfaces defining a preselected axial width. The tread belt is

mounted on a tire carcass having a radially outer peripheral portion, a facing pair of sidewalls, and a radially inner base portion. A buttressed deflector of preselected cross sectional configuration extends axially outwardly from at least one sidewall of the tire carcass a distance axially beyond the tread belt of from 5 to $7\frac{1}{2}\%$ of the preselected axial width for deflecting external objects away from the sidewall.
